UNITED SHOE MACHINERY COMPANY, OF PATERSON, NEW JERSEY, A CORPORA-
TION OF NEW JERSEY.

STARTING AND STOPPING MECHANISM FOR PRESSES.

1,194,379.

Specification of Letters Patent. Patented Aug. 15, 1916.

Application filed June 8, 1912. Serial No. 702,481.

To all whom it may concern:

Be it known that we, JOSEPH GOULDBOURN and ARTHUR BATES, subjects of the King of England, residing at Leicester, Leicestershire, England, have invented certain Improvements in Starting and Stopping Mechanisms for Presses, of which the following description, in connection with the accompanying drawings, is a specification, like reference characters on the drawings indicating like parts in the several figures.

This invention relates to starting and stopping mechanisms for presses and particularly to such mechanism for controlling presses of the type sometimes called "revolution presses," the term "revolution press" being indicative of the fact that in presses of this type the pressing operation is performed and the parts restored to their inoperative positions during a single revolution of the driving shaft, a fly wheel upon said shaft taking the place of the usual train of gears to reduce the power requirements of the machine.

The press to which the term "revolution press" is applied is of the beam or cross-head type and is commonly used with cutting-out dies for cutting sheet material, especially the thicker sheet materials, or when it is desired to cut several thicknesses at one operation. Presses of this type, as usually constructed up to the present time, have been provided with means for bringing them to rest at the end of a complete revolution of the main shaft, provided the actuating mechanism be released by the operator in due season. If, however, in presses of this type as hitherto constructed, the operator failed to release the actuating mechanism quickly enough, a second pressing operation would be performed, sometimes with disastrous results to the work or injury to the operator. Moreover the danger of repeating, in presses of this type as hitherto constructed, necessitated more attention on the part of the operator to the manner in which he operated the machine, and therefore rendered his work more arduous and reduced both the efficiency of the operator and the efficiency of the machine.

An object of the invention is to improve the operation of presses and particularly of presses of the type above described in the

respects noted, whereby an increased output of work may be obtained and the danger of 55 injury to the operator by repeating may be entirely obviated.

A particular object of the invention is to render machines of this type absolutely non-repeating and also to so arrange the controlling mechanism that the machine cannot be actuated at all when the parts are not properly adjusted to insure proper action of said controlling mechanism.

With the foregoing and other objects in 65 view, the invention is herein shown as embodied in a press of the particular type above specified, the illustrated embodiment comprising means for unclutching the press from the source of power at the completion 70 of the pressing operation independently of the operation of the treadle, or other manually controlled element of the actuating means, and, in addition, means for interposing a stop or abutment in the path of 75 movement of a coöperating stop provided on a moving part of the machine whereby the latter will be stopped substantially positively in the event that the brake fails to bring the said part to rest before the two 80 stop members come into engagement with each other.

A particular feature of the invention is the provision of an abutment or stop, arranged to coöperate with a stop on a moving 85 part of the machine, which is so connected with the brake mechanism that upon the stop being brought into engagement with the abutment the action of the brake member upon the brake surface will be amplified. 90 Moreover, the abutment is preferably connected with the clutch mechanism in such manner that, should the stop be brought against the abutment with any considerable force, the clutch mechanism will be held 95 from operation by the treadle or other manually controlled member of the actuating means until the driving shaft has been turned slightly in a direction opposite to that which effects the operation of the press. 100 This arrangement provides a "tell-tale" which will thus indicate that the brake is not properly adjusted, or that the brake surface is worn to such an extent as to require readjustment of the brake band.

Other features and objects of the inven-

tion will be apparent when the following description and claims are considered in connection with the accompanying drawings, in which,—

5 Figure 1 is a front elevation of a press of the particular type above referred to, having embodied therein the improvements which constitute the present invention; Fig. 2 is a detail view, partly in section, showing 10 an end elevation of the clutch controlling mechanism, viewed from the right hand end of the machine; Fig. 3 is a detail perspective, partly in section, showing the clutch actuating connections with the treadle and 15 the means for interrupting these connections as the beam or platen returns to its inoperative position; and Fig. 4 is a detail end elevation, viewed from the left-hand side of the machine, showing the brake and 20 the coöperating stops by which the machine is positively prevented from repeating in the event that the brake does not operate properly.

In the machine in which the invention is 25 shown as incorporated a frame 2 supports a table 4 upon which is carried a cutting block 6 on which the work is placed that is to be operated upon by the dies or other cutting means. Above the table is a beam or 30 platen 8 carried by four rods 10 located approximately at its corners. The rods 10 are guided for vertical movement in suitable guides 12 on the machine frame and connections are provided between the rods and 35 eccentrics 14 upon the main driving shaft 16 whereby the platen 8 may be moved toward the table so as to engage the knives and effect the cutting operation.

At one end of the driving shaft 16 is a 40 clutch mechanism by which the machine is connected with a source of power, and at the other end of the shaft is a braking and stopping mechanism and operative connections are arranged between the two mechanisms to cause their action to be correlated.

The clutch mechanism comprises a coned clutch member 18 keyed upon the driving shaft and fixed against longitudinal movement thereon, and a driving pulley 20 loose 50 upon the driving shaft and arranged for movement longitudinally thereof into engagement with the clutch member 18, the driving pulley being provided with an internal conical surface adapted to coöperate 55 with the external conical surface of the member 18. The movement of the driving pulley lengthwise of the shaft into and out of engagement with the coned clutch member 18 is controlled by a lever 22 fulcrumed 60 at 24 upon a bracket 26 on the side of the machine frame, the lever 22 being forked at its lower end and receiving in openings in the two fork members the trunnions 28 of a thrust washer 30 which enters a groove 65 32 in the hub 34 of the pulley 20. The up-

wardly extending arm of the lever 22, which, for the sake of convenience, is hereinafter referred to as the "clutch lever," is connected with a laterally movable rod 36 that is guided by any suitable means, such, 70 for example, as a radius link 38 centered upon the machine frame. The laterally movable rod 36 is acted on by a spring 40 which will move it in such a direction that the clutch lever will be turned so as to 75 thrust the driving pulley 20 into engagement with the coned clutch member 18 and cause the machine to be operated when the clutch is not under the control of means that will be hereinafter described.

Above the point on the clutch lever 22 at which the laterally movable rod 36 is connected to said lever, one end of a pair of toggle links 42, 44 is pivoted, the other end of the other link 44 being connected by a 80 pin and slot connection with the upper end of a lever 46 centered at 48 on a bracket 50 secured to the machine frame. This lever, which will be referred to as the "platen controlled lever" is connected at its lower end 90 by a link 52 with a bracket 54 bolted upon one of the rising and falling rods 10 that supports the platen and by the movement of which the latter is moved toward and from the table 4. The bracket, link and platen controlled lever are so arranged with relation to one another that when the platen is raised to its inoperative position the said lever, acting through the toggle links when these are in their straightened position, will 95 thrust the upper end of the clutch lever 22 outward against the influence of the spring 40 acting on the laterally movable rod 36 so that the lower end of the said clutch lever will withdraw the pulley 20 from engagement with the coned clutch member 18 by the time that the platen has approximately reached its highest position.

To start the press into operation, means is provided to break the toggle 42, 44 so that the spring 40, acting on the laterally movable rod 36, will turn the clutch lever 22 in such a direction that the driving pulley 20 will be caused to engage the coned clutch member 18. This means comprises, according to this embodiment of the invention, a pendent link or finger 56 pivoted upon the toggle link 42 near the knee joint of the toggle. A spring 58 connects the pendent link with a projection 60 on the upper end 110 of the clutch lever 22, the tendency of the spring being to lift the said pendent link and maintain the toggle in its straightened condition. A stop is preferably provided 115 for preventing the toggle from breaking 120 upwardly.

At the lower end of the pendent link 56 is a projection 62 which is adapted to be engaged by a tooth 64 formed on a clutch tripping or actuating lever 66 also ful- 125

crummed at 48 upon the bracket 50. The other arm of the clutch tripping or actuating lever 66 is connected by a rod 68 to a treadle 70. When the treadle rod 68 is depressed by the treadle the tooth 64 on the clutch trip lever 66 will engage the projection 62 on the pendent link 56 and pull the said link down against the action of the spring 58, thereby breaking the toggle 42, 44 and thus allowing the spring 40, acting on the laterally movable rod 36, to turn the clutch lever 22 in such a direction as to cause the driving pulley 20 to engage the coned clutch member 18 and start the press in operation.

To prevent the driving shaft 16 from making more than a single revolution even if the treadle is maintained in its clutch actuating position, a tappet screw 72 is provided on the clutch lever 22 which screw engages a face of the pendent link 56 or a face of the projection 62. As the pendent link 56 is pulled down through its connection with the treadle, as already described, the tappet screw 72 will bear against the face of the link and by the time the clutch lever 22 has moved far enough to put the clutch into operation the pendent link 56 will be pushed by the screw to an extent sufficient to disengage the projection 62 from the tooth 64 on the clutch trip lever 66, whereupon the spring 58 connected with the pendent link will raise the same and straighten the toggle 42, 44 as soon as the distance apart of the ends of the platen controlled lever 46 and the clutch lever 22 permits the said toggle to be straightened.

To insure that the driving pulley 20 is retained in engagement with the coned clutch member 18 throughout a complete operation of the press and to prevent the premature unclutching of the pulley 20 from the shaft 16 by the straightening of the toggle 42, 44 when the pendent link 56 is released, a positive locking device is provided to hold the laterally movable rod 36 in the position into which it is moved by its spring when starting the press. Conveniently the lock consists of a cam surface 74 forming part of the bracket 54 hereinbefore referred to as bolted upon one of the rising and falling rods 10 of the platen. The cam surface 74 engages a roller 76 or the like on the laterally movable rod 36 and is so shaped that while the said rod is held from movement during the depression of the platen it will be left free to move when the platen reaches its uppermost position.

The brake mechanism is coupled with the clutch mechanism through the laterally movable rod 36 which preferably extends across the machine from side to side. The said rod is connected at its left-hand end, see Fig. 1, with the vertical arm of a bell-crank lever 78 centered upon a bracket 80

secured to the machine frame. The horizontal arm of the bell-crank lever 78 is coupled by a link 82 with the outer end of a rocker frame 84 pivotally mounted at 86 upon the frame of the machine or on the bracket aforesaid. Pivotally connected to the rocker frame, also at its outer end, is one end of a band brake 88 that partially surrounds a brake drum 90 secured on the shaft 16. The other or stationary end of the brake is adjustably carried by an upstanding lever 92 pivoted at 94 upon the machine frame. It will be seen from the foregoing description that when the laterally movable rod 36 is propelled by its spring 40 in the direction that moves the driving pulley 20 into engagement with the coned member 18 the bell-crank lever will be turned on its center so as to lower its horizontal arm and thereby swing the rocker frame 84 downward on its pivot whereby the brake band 88 will be slackened on the brake drum 90.

To prevent the driving shaft from overrunning should the band brake 88 fail to exercise sufficient braking action, a stop 96 is provided on the brake drum, which stop is so located on the drum as to come into contact with or into close proximity to an abutment 98 at the time the press is stopped, the said abutment being removed automatically from the path of the stop 96 when the machine is in operation. The abutment 98, according to this embodiment, is constituted by a pendent arm that is pivoted at 100 upon the outer end of the rocker frame 84 and hangs downward when the brake is applied in such position that its free end will be in the path of the stop 96 on the brake drum. To remove the end of the pendent arm 98 from such position when the brake is slackened and the machine is started, the said arm is provided with a cam piece 102 which, as the arm is lowered, engages an adjustable stud 104 on the machine frame and is thereby deflected out of the path of the stop 96 on the drum preferably in opposition to a spring 106 which connects the pendent arm with the frame and tends to maintain the said arm in the position in which it will engage the stop. The arrangement that the abutment 98 is attached to the rocker frame 84, to which also the end of the brake band 88 is attached, provides means such that should the band brake fail to stop the press and the stop 96 on the brake drum should be brought forcibly against the pendent arm 98, the latter will be moved upward and the rocker frame 84 so turned as to amplify the pressure already applied to the band brake. Moreover, when the pendent arm 98 is forced upward beyond a predetermined amount by the stop 96 on the brake drum, the clutch mechanism cannot be operated, even if the treadle be actuated, and the toggle 42, 44, herein-

130

before described, cannot be broken by reason of the fact that the laterally movable rod 36 will not be free to move under the influence of the spring 40 which normally tends to move it and the clutch lever 22 to clutch the driving pulley 20 to the coned member 18.

To start the press into operation after it has been thus stopped it is necessary that the 10 driving shaft 16 shall be revolved slightly in a direction opposite to that in which the press is operated in order to free the pendent arm 98 from the stop 96 on the brake drum, and thus a tell-tale is provided to show that 15 the brake is not properly adjusted or that the brake surface is worn to such an extent as to require the adjustment of the brake band.

The operation of the press, briefly recapitulated, is as follows: Assuming the 20 platen 8 to be raised and the driving pulley 20 to be out of contact with the cone member 18 on the driving shaft 16, the work and dies are positioned on the block 6. The operator 25 then depresses the treadle 70 which, through the clutch trip lever 66, tooth 64 and projections 62, pulls down the pendent link 56 and breaks the toggle 42, 44. This permits the spring 40 to move the laterally movable 30 rod 36 which at one side of the machine turns the clutch lever 22 to cause the loose pulley 20 to engage the cone member 18 and at the other side of the machine lowers the rocker frame 84, thereby slackening the 35 brake band on the brake drum 90 and at the same time removing the pendent arm 98 from the path of the stop 96 on the brake drum. The engagement of the tappet screw 72 with the pendent link 56 as the latter is 40 pulled down by the treadle causes the projection 62 to be moved out of engagement with the tooth 64 as the clutch lever 22 moves in a counter-clockwise direction in Fig. 1, so that the toggle is permitted to 45 assume its straightened position irrespective of the action of the treadle as soon as the movement of the platen controlled lever 46 leaves space enough between the said lever 46 and the clutch lever 22 for the straightening of the toggle. The pin and slot connection between the toggle and the platen 50 controlled lever provides lost motion for the latter after the toggle has been straightened. During the greater part of the movement of the platen 8, the laterally movable rod 36 is 55 locked from movement by the cam surface 74 on the platen rod engaging the roller 76 on said laterally movable rod. During the continued rotation of the driving shaft and 60 after the cutting operation has been effected, the raising of the platen will turn the platen controlled lever 46 until the lost motion of the toggle therewith has been taken up, whereupon, the cam 74 being removed from 65 the roller 76 on the laterally movable rod 36,

the straightened toggle 42, 44 will thrust the top of the clutch lever 22 outward and so disconnect the loose pulley 20 from the cone member 18 to stop the machine. At the same time the laterally movable rod 36 will be pulled toward the right by its connections with the clutch lever 22, and, through the bell crank 78 and the rocker frame 84 with which it is connected, it will cause the brake band 88 to be drawn against the drum and at the same time will position the end of the arm 98 in the path of the stop 96 on the brake drum so as to insure stopping of the machine if the said parts come into contact.

Having described our invention, what we claim as new and desire to secure by Letters Patent of the United States is:

1. In a machine of the class described, driven mechanism, driving means, and starting and stopping mechanism comprising, in combination, a clutch through which connections may be effected between said driven mechanism and said driving means, means, comprising a brake, for preventing more than one operation of the machine for a single actuation, and means for preventing overthrow of the machine, said last-mentioned preventing means being rendered operative by the action of said first-mentioned preventing means and being arranged to operate only after said first-mentioned preventing means has operated.

2. In a machine of the class described, driven mechanism, driving means, and starting and stopping mechanism comprising, in combination, a clutch through which connections may be effected between said driven mechanism and said driving means, means connected with the driven mechanism for maintaining said clutch operative until the machine has substantially completed an operation, means, comprising a brake, for preventing more than one operation of the machine for a single actuation, and means for preventing overthrow of the machine, said last-mentioned preventing means being rendered operative by the action of said first-mentioned preventing means and being arranged to operate only after said first-mentioned preventing means has operated.

3. In a machine of the class described, starting and stopping mechanism comprising a clutch through which connections may be effected with a source of power, a brake, means for disconnecting said clutch and applying said brake, and means, arranged to operate only in case of overthrow of the machine, for increasing the braking action of said brake.

4. In a machine of the class described, driven mechanism, driving means, and starting and stopping mechanism comprising, in combination, a clutch through which

- connections may be effected between said driving mechanism and said driving means, a brake, means connected to said driven mechanism for disconnecting said clutch mechanism for disconnecting said clutch 5 and applying said brake at the end of a complete operation of said mechanism, and means also connected to said mechanism and operated therefrom to increase the braking action of said brake in the event of a tendency of said mechanism to pass its normal position of rest.
5. In a machine of the class described, driven mechanism, driving means, and starting and stopping mechanism comprising, in combination, a clutch through which connections may be effected between said driven mechanism and said driving means, a brake, automatic means for disconnecting said clutch after a single operation of the machine and applying said brake, and means connected with said brake and controlled by said driven mechanism for increasing the braking action of said brake in the event of a tendency of said driven mechanism to pass 10 its normal position of rest.
6. In a machine of the class described, a rotatable member, a brake arranged to act upon said member, a stop carried by said member, a second stop connected to said 15 brake and arranged to be interposed in the path of movement of said first stop when said brake is applied, said connections being arranged to increase the braking action of said brake if said stops contact.
7. In a machine of the class described, the combination, with a rotatable driven member, a rotating driving member, means for effecting an operative connection between said members, a stop carried by said 20 driven member, and a brake arranged to act upon said driven member, of means for interrupting the connection between said members, applying said brake to said member, and interposing a stop in the path of movement of the stop on said driven member, and connections between said brake and said interposed stop whereby the braking action of said brake is increased when said 25 stops contact.
8. In a machine of the class described, the combination with driven mechanism and driving means, of a clutch through which connection may be effected between said mechanism and said means, a brake for stopping said mechanism when said clutch is disconnected, means acting automatically to disconnect said clutch and to apply said 30 brake to stop said mechanism after a single operation, a stop arranged to be moved into position to prevent overthrow of said mechanism beyond its position of rest, and connections between said mechanism and said stop for moving said stop into operative position.
9. In a machine of the class described, 35 the combination with relatively reciprocating parts and means for operating said parts including a clutch through which connections may be effected with a source of power, of a brake, means acting automatically to disconnect said clutch and to apply said brake after a single reciprocation of said reciprocating parts, means for automatically introducing a stop into the path of movement of said operating means to prevent a relative movement of said reciprocating parts beyond their relative positions of rest, and connections between said stop and said brake whereby the braking action of said brake is increased in the event of a 40 tendency of said machine to overthrow.
10. In a machine of the class described, a reciprocating member and mechanism for effecting the reciprocation of said member, including a clutch through which connections may be effected with a source of power, means for automatically disconnecting said clutch and applying a brake after a single operation of said member, means for automatically interposing a stop in the path of movement of an element of said mechanism to prevent a movement of said member beyond its position of rest, and connections between said stop and said brake whereby the braking action of said brake is increased 45 in the event of a tendency of said member to pass its position of rest.
11. In a machine of the class described, a reciprocating member, and means for moving said member toward and away from the work, including a clutch through which connections may be made with a source of power, in combination with clutch controlling mechanism operated from said member, brake mechanism, connections between the clutch controlling mechanism and the brake mechanism whereby the brake is applied when the clutch is disconnected, and means for preventing overthrow of the parts comprising a stop arranged to be brought into operative position as the clutch is disconnected, said stop being so connected to said 50 brake mechanism that if its stopping function be called into play it will increase the action of said brake mechanism.
12. In a machine of the class described, the combination with driven mechanism, driving means, a clutch through which connections may be effected between said mechanism and said means, and a brake for stopping said mechanism when said connections are interrupted, of means operating in the event of overthrow of said mechanism to increase the braking action of said brake, and a single actuating means constructed to render said clutch operative and simultaneously to render said brake and said overthrow preventing means inoperative.
13. In a machine of the class described, the combination with driven mechanism, 55

- comprising a reciprocating member, driving means, a clutch through which connections may be effected between said mechanism and said means and a brake for stopping said mechanism when said connections are interrupted, of means connected to said reciprocating member for positively releasing said clutch as the reciprocating movement of said member is completing and for 5 positively applying said brake, and means, also rendered operative as said member is completing its movement, for increasing the braking action of said brake in the event that said member passes its position of rest.
14. In a machine of the class described, the combination with driven mechanism, comprising a reciprocating member, driving means, a clutch through which connections may be effected between said mechanism and said means and a brake for stopping said mechanism when said connections are interrupted, of means connected to and operated by said reciprocating member for maintaining said clutch positively in operative condition throughout substantially the whole of the reciprocating movement of said member, and for moving said clutch positively into inoperative condition and for positively applying said brake as the reciprocating movement of said member is completing, and means, operating in the event 10 of overthrow of said member, for increasing the braking action of said brake.
15. In a machine of the class described, the combination with a driven mechanism, comprising a reciprocating member, driving means, a clutch through which connections may be effected between said mechanism and said means, and a brake for stopping said mechanism when said connections are interrupted, of means connected to and operated by said reciprocating member for maintaining said clutch positively in operative condition throughout substantially the whole of the reciprocating movement of said member, and for moving said clutch positively into inoperative condition and for positively applying said brake as the reciprocating movement of said member is completing, and means, also rendered operative through 15 connection with said reciprocating member, for increasing the braking action of said brake if said member passes its position of rest.
16. In testimony whereof we have signed our names to this specification in the presence of two subscribing witnesses.
